(57) **CLAIM**

The ornamental design for a scorecard graphical user interface for a portion of a display screen, as shown and described.

DESCRIPTION

FIG. 1A is a view of the left portion of the scorecard graphical user interface for a portion of a display screen showing our new design; and,

FIG. 1B is a front view of the right portion thereof.

The broken lines showing the unclaimed text are included for the purpose of illustrating environment and form no part of the claimed design. The portion of a display screen shown in broken line is included for the purpose of illustrating environment and forms no part of the claimed design.
